US00D798748S

(12) **United States Design Patent** (10) **Patent No.:** **US D798,748 S**
(45) **Date of Patent:** **** Oct. 3, 2017**

(54) **METRONOME**

(71) Applicant: **Clikbrik, LLC**, Brooklyn, NY (US)

(72) Inventors: **Konrad Meissner**, Brooklyn, NY (US);
Edwin Booth, Brooklyn, NY (US);
Carla Diana, Philadelphia, PA (US);
Michael Glaser, Philadelphia, PA (US)

(73) Assignee: **Clikbrik, LLC**, Brooklyn, NY (US)

(**) Term: **15 Years**

(21) Appl. No.: **29/547,322**

(22) Filed: **Dec. 2, 2015**

(51) LOC (10) Cl. **10-03**

(52) U.S. Cl.

USPC **D10/43**

(58) **Field of Classification Search**

USPC D10/43; D9/435

CPC . H04R 5/012; H04R 1/02; H01R 9/05; A63H
